SHOE POLISHING STAND

Filed June 5, 1924

UNITED STATES PATENT OFFICE.

WILLIAM H. WHITE, OF QUINCY, MASSACHUSETTS, ASSIGNOR TO REGAL SHOE COMPANY, OF WHITMAN, MASSACHUSETTS, A CORPORATION OF MASSACHUSETTS.

SHOE-POLISHING STAND.

Application filed June 5, 1924. Serial No. 717,984.

This invention relates to shoe polishing stands of the kind in which the customer having the shoes polished is seated on a bench or chair placed on a platform and 5 rests his shoe on a suitably located foot rest for support during the polishing of the shoe by the attendant.

It is the object of the present invention to provide a simple and instantly adjustable 10 device of this character which is so constructed that it can be raised to the desired level to support the foot during the polishing operation, and which can be dropped out of the way to prevent obstructing the customer in his descent from the raised platform.

To this end the invention comprises, generally speaking, in combination with a platform or base, a bracket secured thereto 20 and a foot-rest comprising an upright or rod provided with a foot-supporting plate or head arranged to have sliding support and engagement with the bracket, whereby the foot-rest may be dropped to the floor 25 of the platform and may be raised to the working position and maintained there while it is in use. These and other features of this invention will be pointed out in the following specification and will be defined in the claims hereto annexed.

In the accompanying drawings I have illustrated a simple and convenient construction and arrangement embodying and illustrating the principles of this invention, in 30 which:

Figure 1 shows, in side elevation, a shoe stand with the foot-rest in working position to support the foot at a convenient level for the polisher.

Figure 2 is an enlarged central section showing the foot-rest supporting bracket and the means for retaining it in position for use.

Figure 3 is a plan view of the foot-rest 45 and the adjacent portion of the platform.

Figure 4 is a cross section of the slide-rod of the foot-rest showing, in dotted lines, the position of the ball detent which holds it in working position.

As is well known, shoe polishing stands

of this character are generally provided with upstanding brackets between which the customer must step in taking his position for shoe polishing or in descending therefrom, and accidents often happen due 55 to catching the foot against these brackets when stepping down from the chair or bench.

In the present invention this objection or defect is overcome by so mounting the foot-rest member that it may be left normally in lowered position where it presents only a thin plate resting flat on the top or floor of the platform, and presenting no obstacle interfering with the customer taking his 60 seat or descending therefrom.

In the form illustrated, I have shown at 1, the usual platform or box which carries a chair or bench 2, on which the customer is seated while having his shoes polished.

A foot-rest supporting bracket 6, comprising preferably a tubular member, is provided intermediate of its ends with an angularly disposed flange or plate 6^a which is secured to the underneath surface of the 70 floor of the platform 1, by means of nails or screws. The angular relation of the attaching member 6^a to the tubular portion of this bracket may be such as suits convenience, but in the drawings this angle is 75 about 45° with the upper portion of the tube above the flange projecting upward through the receiving hole in the floor to lie flush with the top of the floor.

The foot-rest comprises, in this case, a 80 slidable arm or rod 3, whose upper end is provided with a foot-supporting plate or member 4, which latter is preferably pivotally connected to the upper end portion of the rod 3 by means of a pivot pin 5 passing 85 transversely through a depending lug or ear 4^a and the opposite side walls of the rod 3, the rod being slotted or notched at its upper end, as indicated in Figures 1 and 3, to receive the ear on the bottom of the foot- 90 plate 4. The upper end of the rod 3 is formed with two angularly disposed faces, one of which lies in a substantially horizontal plane, as shown at 3^a, and the other 95 of which lies at an angle thereto to form a 100

stop 3^b against which the bottom of the foot-plate 4 abuts when sustaining the foot of the customer.

It will be seen that when the foot-rest is lowered to the position shown in dotted lines in Figure 1, the foot-plate 4 rests flat on the floor of the platform, while when the foot-rest is in working position the foot plate 4 accommodated itself to the proper 10 angle to suitably support the shoe being polished.

To avoid delay, consequent upon manipulation of adjusting members, I prefer to use an automatically acting detent or retaining means for supporting the foot-rest in its proper raised position. As shown in Figure 2, the rod or arm 3 is formed on its underside with a longitudinal groove 3^c, which terminates a short distance above the 20 lower end of said rod. A set screw 11, with preferably a rounded inner end, is inserted through a threaded hole in the tubular sleeve or bracket 6 so as to form a key or spline projecting into this groove sufficiently 25 to guide the rod in its sliding movement and prevent its accidental withdrawal in case the attendant pulls it forward too far.

The foot-resting supporting bracket is also provided, on its under side, with an internally threaded boss 6^b in which is adjustably secured a hollow milled end screw 8 inside of which is placed a ball 9 against which presses a compressed helical spring 10, so that the ball acts as a yielding plunger 35 seating itself under pressure in the longitudinal groove 3^c. At a suitable location there will be formed one or more sockets 3^d directly in the central line of the groove 3^c, and somewhat deeper than the groove and 40 of a size to receive the ball plunger 9, when the rod 3 is raised sufficiently to bring the socket into registry with said ball plunger. The socket is sufficiently shallow so that, under a moderately strong direct axial thrust, 45 the slide-rod 3 will be automatically disengaged.

Since the thrust of the foot is largely transverse to the length of the slide-rod 3 it does not require a very strong pressure 50 upon the plunger 9 to retain the foot-rest at the proper level and allow its easy disengagement by a downward push on the part of the operator. It will, therefore, be seen that no manipulation of fastening devices is 55 required since, after the customer has taken his seat, the attendant can instantly pull up the foot-rest to working position, and after the polishing operation is over he can easily push it down into lowered position flat on 60 the floor so as to afford no obstruction whatever to the customer from his stepping down from the stand. By merely adjusting the screw 8 the desired pressure upon the plunger may be obtained.

65 While described as a stand for shoe pol-

ishing service, the above described device is equally adapted for use in shoe stores for trying on and fitting shoes to customers.

What I claim is:

1. In a shoe polishing stand, the combination with a raised platform provided with a seat, of a foot-rest mounted on said platform in front of the seat and embracing a bearing bracket having an oblique downwardly and rearwardly inclined sleeve, a rod 70 slidably mounted in said sleeve, means to releasably maintain said rod in raised service position, a foot-rest plate hinged to the forwardly projecting upper end of said oblique rod, a stop for said plate formed on the rod below the point of attachment of the plate, to allow the plate to be inclined to receive the foot of a person occupying said seat, the rod and the foot-rest being shiftable to lowered position to allow the foot-rest to lie flat on the platform, thereby presenting no obstruction to one mounting to or descending from the seat.

2. In a stand for shoe polishing or the like, the combination with a platform having a rearwardly disposed seat, of a bracket secured into the floor of the platform with its upper portion substantially flush with the top of said floor, a slide-rod supported to slide in said bracket at a forwardly inclined angle to the plane of the floor, a foot-supporting plate pivotally attached to the upper end of said rod and adapted to engage with either of two faces formed at the upper end of said rod, thereby supporting 95 the foot-plate at the appropriate angles to receive the foot when the rest is raised and to lie flat on the platform when the rest is lowered.

3. In a stand for shoe polishing or the like, the combination with a platform provided with a seat at its rear, a foot-rest and a supporting rod therefor arranged in front of the seat, the rod being mounted to incline forwardly from said seat and slidably up 100 and down in the direction of such inclination, and a self-locking means for retaining said rod in raised position, said locking means being yielding and releasable by an endwise pressure against the rod.

4. The combination with a platform and a seat, an oblique forwardly inclined slide-rod mounted forwardly of said seat, a foot-rest plate pivotally attached to the upper end of said slide-rod and tiltable to an inclined position to receive a foot of the person seated, a yielding detent engaging said rod to releasably sustain said rod in raised position and permitting downward movement thereof upon application of pressure 115 axially of and at the outer end of said rod.

5. An attachment for a shoe polishing stand, embracing a bracket formed with a sleeve and adapted to be secured to the floor 120 of the platform, a slide-rod mounted in said 130

sleeve to be raised and lowered therein and carrying at its upper end a foot-supporting plate, a self-acting ball detent arranged in said bracket to automatically engage depressions in the rod and support the slide rod in raised position, said ball being releaseable by excess pressure endwise on the slide-rod and means providing a spline and groove en-

gagement between said bracket and said slide-rod to prevent the slide-rod from turning and from being withdrawn externally from the bracket, substantially as described. 10

In witness whereof, I have subscribed the above specification.

WILLIAM H. WHITE.
